(57) **CLAIM**

The ornamental design for a bread, as shown and described.

DESCRIPTION

Fig. 1.1 is a perspective view of a bread, showing my new design;

Fig. 1.2 is a front view thereof;

Fig. 1.3 is a top view thereof;

Fig. 1.4 is a bottom view thereof;

Fig. 1.5 is a right view thereof;

Fig. 1.6 is a cross-sectional view thereof, taken from lines 1.6-1.6 in Fig. 1.3; and

Fig. 1.7 is a cross-sectional view thereof, taken from lines 1.7-1.7 in Fig. 1.2.

The evenly-spaced broken lines in Figs. 1.1-1.2 and 1.4-1.6 illustrate portions of the bread that form no part of the claimed design. The dash-dot-dash broken lines in Figs. 1.1-1.2 and 1.5 illustrate the boundary of the claimed design which forms no part thereof. The left side view is identical to the right side view, and the back view is identical to the front view; therefore, views are omitted.
